CLAIM

The ornamental design for a crib as shown and described.

DESCRIPTION

FIG. 1 is a perspective view of the crib;

FIG. 2 is a front elevational view of the crib;

FIG. 3 is a rear elevational view of the crib;

FIG. 4 is a left side elevational view of the crib;

FIG. 5 is a right side elevational view of the crib;

FIG. 6 is a top plan view of the crib; and,

FIG. 7 is a bottom plan view of the crib.

The broken line portions of the drawings are included to show portions of the article that form no part of the claimed design and represent environmental structure only.

1 Claim, 7 Drawing Sheets(56)
